STOCKING GUIDING DEVICE FOR USE WITH SEWING MACHINES

Application filed August 18, 1927, Serial No. 213,738, and in Great Britain September 17, 1928.

This invention relates to an improved stocking guiding device for use with sewing machines, particularly overhead sewing machines of the so-called scale-pan type, and 5 aims to provide a construction such that the pivoted guide proper can be set close to the needle so as to insure perfect stitching though free to be swung aside, for instance to receive work to be stitched.

10 According to the invention the guide proper, comprising as usual a flat arm or plate is secured at the end remote from the stitching mechanism to a frame having perforated lugs strung on a vertical pin that also penetrates perforated lugs on a bracket having lugs apertured for penetration by a vertical spindle sustained by a pedestal or the like, the lugs on the frame and on the bracket forming in effect a toggle device, it being understood that the described arrangement is 15 such as to permit of endwise bodily movement of the arm or plate as well as oscillatory movement around a vertical axis.

The bracket member is influenced by a coil spring surrounding the pedestal and urging the guide toward operative position.

20 Stops, which may be adjustable, are provided for limiting the endwise movement of the guide in both directions.

The spring may be arranged to act so as to return the guide automatically to operative position, thereby avoiding liability to accident.

In the accompanying drawings which illustrate a device according to the invention, Figs. 1 and 2 are elevations at right angles to one another of the stocking-guide support. Fig. 3 is a section on the line 3—3 of Fig. 2. Figs. 4 and 5 are, respectively, an elevation and a plan drawn to a smaller scale showing the stocking-guide proper mounted on the support.

The apparatus shown includes a stocking-guide proper constituted by a flat arm or plate 1 secured at one end to a frame member 2 having perforated lugs 3, 4 strung on a vertical pivotal pin 5 penetrating perforated lugs 6, 7 on a swing bracket 8 having lugs 9, 10 apertured for penetration by a vertical spindle 11 sustained by a pedestal 12.

The guide-arm 1 is attached to the frame 2 by clamping screws 13, 14 penetrating apertures on the arm and threaded into the frame and pins 15, 16 fixed in the frame and penetrating apertures in the arm.

It will be seen that the arrangement is such that a restricted amount of endwise retracted movement of the guide-arm is permitted around the pivotal pin 5 as well as oscillatory movement around the axis of the spindle 11.

25 Lateral projections 17, 18, integral with the bracket 8, cooperate with screw-pins 19, 20, threaded through lugs 21, 22, integral with the frame 2, to restrict endwise retracted movement of the arm 1.

The setting of the screw-pins 19, 20, which are fitted with nuts 23, 24, determines the amount of endwise movement that may be imparted to the guide-arm.

30 The bracket or controlling member 8, having the parallel pivotal connections 5 and 11 with the pedestal 12, is influenced by a coil-spring 25 anchored at 26 to the pedestal 12 and engaging a pin 27 fixed to the bracket.

Figs. 4 and 5 show the guide-arm in operative position cooperative with the usual sewing machine feed-cups 28 with its delivery end terminating in the space intermediate the feed-cups. The action of the coil-spring 25 is to hold the guide-arm in operative position and to return it automatically to operative position after it has been swung aside to receive work to be stitched, it being understood that before the guide-arm can be swung aside into the position shown in dotted lines in Fig. 5 it must be moved endwise to clear the forward feed-cup 28.

Having thus set forth the nature of the invention, what we claim herein is:

1. In combination, a guide adapted to receive a tubular article and having a free and unobstructed delivery end, a support, and means intermediate said support and the delivery end of the guide adapted to sustain the latter for bodily endwise and sidewise swinging movement at a substantially constant level.

2. The combination with sewing machine feed-cups, of a stocking guide comprising a

100

support, a guide-arm mounted on and movable bodily endwise relative to and circularly around said support, said guide having an unobstructed free end terminating closely adjacent said feed-cups.

3. In combination, a guide adapted to receive a tubular article and having a free and unobstructed delivery end, a pedestal, a member mounted on said pedestal for movement at a fixed level relative to the latter, and a pivotal connection between said member and guide.

4. In combination, a guide adapted to receive a tubular article and having a free and unobstructed delivery end, a pedestal, and a member intermediate said guide and said pedestal having parallel pivotal connections with the guide and pedestal, respectively.

5. The combination with sewing machine feed-cups, of a pedestal, a stocking guide having a free and unobstructed delivery end terminating, when in operative position, in the space intermediate said feed-cups, and a controlling member having parallel pivotal connections with said pedestal and said stocking guide insuring retraction of the latter from said space in a direction opposite the direction of feed and for movement laterally of its operative position.

30 6. The combination with sewing machine feed-cups, of a pedestal, a guide adapted to receive a tubular article and having a free and unobstructed delivery end terminating, when in operative position, in the space intermediate said feed-cups, means intermediate said pedestal and the delivery end of the guide adapted to sustain the latter for bodily endwise and sidewise swinging movement at a substantially constant level, and means for 35 yieldingly maintaining the delivery end of said guide in operative position intermediate said feed-cups.

In testimony whereof, we have signed our names to this specification.

45 HERBERT CORRALL.
JAMES HEGGIE.
